UNITED STATES PATENT OFFICE.

HENRY BREHMER, OF STAPLETON, ASSIGNOR TO DAVID WOLFE BRUCE,
OF NEW YORK, N. Y.

DESIGN FOR TYPE.

SPECIFICATION forming part of Design No. 16,002, dated March 31, 1885.

Application filed December 13, 1884. Term of patent 14 years.

To all whom it may concern:

Be it known that I, HENRY BREHMER, (assignor to DAVID WOLFE BRUCE,) of Stapleton, county of Richmond, and State of New York, have invented a new Design for a Font of Printing-Type, of which the following is a specification.

The nature of my design is clearly shown in the accompanying typographic impression, to which reference is made; and it consists of an ornamental letter shaded upon the left and above by a light line, and upon the right and below by a heavy line. The top shade-line, as in the B, C, D, O, P, Q, R, and S, is provided with the heavy dot, as shown upon the right, and the bottom shade-line, as in the B, C, D, J, O, S, and U, is disconnected from the right-hand shade-line, and is inclined upon the right, as shown.

The character of the design is preserved in the punctuation-marks, the numerals, and the dollar and pound-sterling marks.

My present design differs from the design

shown in specimen-book of Boston Type Foundry, 1876, example 202, in that it is a more condensed letter, and the shading in that example is of the block-letter character, being much deeper or wider, is continuous, and does not present the features described and shown in the present application. 30

I claim—

The design for a font of printing-type, consisting of a condensed ornamental letter shaded upon the left and above by a light line, and upon the bottom and right by a heavy line, the shade-lines following the configuration of the letter, and the top shade-line in the B, C, D, O, and S being provided with the heavy dot, as shown, and the bottom shade-line in the B, C, D, J, O, S, and U being inclined upon the right, as shown.

HENRY BREHMER.
